TUBE CLEANING DEVICE

Edward J. Mackiewicz, Garfield, and Arthur L. Lindow, Solon, Ohio, assignors to Cleveland Pneumatic Industries, Inc., Cleveland, Ohio, a corporation of Ohio

Application December 19, 1955, Serial No. 553,993

2 Claims. (Cl. 15—321)

This invention relates to cleaning devices in general and more particularly to a new and improved rotary brush adapted to clean tubes, cylinder bores and the like.

It is an important object of this invention to provide a rotary brush particularly suited for cleaning tubes, the bores of cylinders or other hollow articles to remove grease, grit and metallic particles therefrom.

It is another important object of this invention to provide a power driven rotary brush which supplies a fog of cleaning solvent at the working area of the brush so that grease and foreign matter will be loosened and flushed out of the article being cleaned.

It is still another object of this invention to provide a rotary brush for cleaning bores and the like in combination with a magnet which picks up and removes metallic particles.

It is still a further object of this invention to provide a tube or bore cleaning device which combines a rotary brush to scour the surface of the bore, a magnet which picks up and retains magnetic particles and means to supply a solvent in the form of fog at the brush working area.

Further objects and advantages will appear from the following description and drawings, wherein:

Figure 1 is a side elevation partially in longitudinal section disclosing the preferred cleaning device according to this invention as it would be used to clean the bore of a cylinder;

Figure 2 is an enlarged view partially in longitudinal section showing the fog producing means; and,

Figure 3 is a fragmentary enlarged view in longitudinal section of the brush showing the magnet mounted therein.

A cleaning device according to this invention provides a grease solvent in a fog form which thoroughly wets the wall of a tube or the like which is to be cleaned. The device also provides mechanical scrubbing to assist the solvent in loosening grease or any other foreign matter so that it may be flushed out of the tube by the solvent. This alone is not always sufficient since fine particles of metal left by the machining operation are often present. These small particles usually retain a small amount of residual magnetism which is developed by the cutting operation which causes the particles to adhere to the walls of the tube and defy the flushing action. We therefore provide a magnet mounted within the brush which will attract the metallic particles away from the tube, imbed them in the brush and retain them there as the brush is withdrawn.

For a clear understanding of the details of the structure and the operation, reference should be made to the drawings wherein Figure 1 shows the preferred cleaning device as it would be used in cleaning the walls of a tubular member which in this case is a cylinder 10. The cylinder 10 has an internal cylinder wall 11 which must be cleaned very efficiently so that a cooperating piston (not shown) will not wear unnecessarily as it slides along

2

the cylinder wall 11. To clean the wall 11 we provide a rotary cleaning device which includes an air motor 12 driving a hollow shaft 13 and a brush 14 mounted thereon. The air motor is supplied with air pressure through a pressure line 15 and a control valve 15' and rotates the shaft 13 and brush 14 which in turn scours the wall 11 of the cylinder 10.

Referring to Figure 2, the shaft 13 is formed with a central bore 16 through which the solvent fog passes to the brush 14. The exhaust ports 17 of the air motor 12 are arranged so that the exhaust air from the motor flows through a nozzle 18 aligned with the bore 16. A mounting member 19, on which the shaft 13 is mounted, is formed with a chamber 21 around the nozzle 18. Mineral spirits or other solvents are supplied through a hose 22 which connects to an annular chamber 23 around the mounting member 19 adjacent to the chamber 21. Fluid communication is provided between the chamber 21 and the annular chamber 23 through radial ports 24 so that the mineral spirits flow into the chamber 21. The jet of exhaust air through the nozzle 18 entrains and atomizes the solvent and carries it down the bore 16 as a fog.

Referring to Figure 3, the brush 14 is supported on the shaft 13 by a threaded ring member 26 which is locked against a collar 27 formed on the shaft 13 by a core member 28 which is in turn threaded onto the shaft 13. The brush 14 itself is made up of a plurality of U-shaped brush elements which cooperate to form a cup shaped brush around the core member 28. The core member 28 is formed with a plurality of ports 29 through which the mixture of exhaust air from the motor 12 and atomized solvent passes from the bore 16 outwardly through the brush 14. Thus the fog solvent is supplied directly to the walls 11 being cleaned by the brush 14.

A coil of wire 31 is wound around the core 28 to form a magnet within the brush 14. In order to supply electrical power to the magnet, we provide lead wires 32 which extend through the bore 16 to a pair of slip rings (not shown) within the end member 33. The slip rings are in turn connected to a source of electrical power through wires 34. Thus electrical power may be supplied to the rotating magnet through the rotating shaft 13.

In operation air pressure is supplied to the valve 15' through the pressure line 15, and mineral spirits are supplied to the chamber 21 through the hose 22. The brush 14 is inserted into the cylinder 10 and the valve 15' is opened. This causes the air motor 12 to rotate the brush 14 and pass exhaust air through the bore 16 in the shaft 13 to the brush 14. The exhaust air passing through the nozzle 18 causes the mineral spirits within the chamber 21 to be atomized to form a fog of solvent which passes through the shaft 13 to the brush 14. The fog wets the surface 11 of the cylinder 10 and with the assistance of the brush 14 loosens the grease or other foreign matter from the wall 11. The solvent then carries the foreign matter and grease out of the cylinder through the open end thereof. Any small metallic particles which tend to adhere to the surface 11 due to their residual magnetism are attracted into the bristles of the brush by the magnet and retained there as the brush is withdrawn from the cylinder. After the brush is withdrawn from the cylinder, the magnet is de-energized and the brush rotated so that the centrifugal force and the action of the fog will automatically clean the brush.

By utilizing the nozzle 18 to atomize the solvent, proper mixing of the solvent is assured even if the pressure of the exhaust air is substantially higher than the pressure of the solvent in the hose 22. In fact, it is even possible to use this structure even when the solvent is at atmospheric pressures because of the pumping action of the jet of exhaust air.

Those skilled in the art will recognize that a cleaning device according to this invention insures that all the foreign matter is removed from the cylinder or other tubular member since the brush and solvent will remove all non-magnetic particles and the magnet removes the magnetic particles which tend to adhere to the cylinder wall and defy normal brushing.

Although a preferred embodiment of this invention is illustrated, it will be realized that various modifications of the structural details may be made without departing from the mode of operation and the essence of the invention. Therefore, except insofar as they are claimed in the appended claims, structural details may be varied widely without modifying the mode of operation. Accordingly, the appended claims and not the aforesaid detailed description are determinative of the scope of the invention.

We claim:

1. A cleaning device comprising a rotary compressed air motor drivingly connected to one end of an elongated hollow drive shaft, a brush adapted to be inserted in cylindrical openings, said brush being mounted on the end of said shaft remote from said motor for rotation by said motor through its connection to said shaft, said motor providing exhaust air, a nozzle in the end of said shaft adjacent to said motor through which said exhaust air flows, a non-rotating housing around said shaft adjacent to said nozzle formed with an annular cavity adapted to be filled with liquid solvent, said shaft being formed with a passage connecting said cavity and the interior of said shaft adjacent to said nozzle through which said liquid solvent flows into said shaft wherein it is mixed with exhaust air forming a liquid solvent fog mixture, said exhaust air carrying said fog mixture along said shaft to said brush.

2. A cleaning device comprising a rotary compressed

air motor drivingly connected to one end of an elongated hollow drive shaft, a brush adapted to be inserted in cylindrical openings, said brush being mounted on the end of said shaft remote from said motor for rotation by said motor through its connection to said shaft, said motor providing exhaust air, a nozzle in the end of said shaft adjacent to said motor through which said exhaust air flows, a non-rotating housing around said shaft adjacent to said nozzle formed with an annular cavity adapted to be filled with liquid solvent, said shaft being formed with a passage connecting said cavity and the interior of said shaft adjacent to said nozzle through which said liquid solvent flows into said shaft wherein it is mixed with exhaust air forming a liquid solvent fog mixture, said exhaust air carrying said fog mixture along said shaft to said brush, and an electro magnet within said brush adapted to attract metal particles into said brush.
